UNITED STATES PATENT OFFICE.

WILLIAM M. MITCHELL, OF LOUISVILLE, KENTUCKY.

RAIL-ANCHOR.

1,292,845.

Specification of Letters Patent. Patented Jan. 28, 1919.

Application filed May 15, 1916. Serial No. 97,589.

To all whom it may concern:

Be it known that I, WILLIAM M. MITCHELL, a citizen of the United States, and a resident of Louisville, in the county of Jefferson and State of Kentucky, have invented 5 certain new and useful Improvements in Rail-Anchors, of which I do declare the following to be a full, clear, and exact description, reference being had to the accompanying drawings, forming a part of this specification.

The present invention has relation to rail anchors or "anti-creepers" designed to prevent the creeping of railway rails along the 15 tracks. An example of the type of rail anchor to which my invention more particularly relates is set forth in Patent No. 1,184,478, issued to me May 23, 1916. The present invention consists in the features of 20 improvement hereinafter described, illustrated in the accompanying drawings and particularly pointed out in the claims at the end of this specification.

Figure 1 is a plan view of my improved 25 rail anchor showing also a portion of a rail to which the anchor is connected and a portion of a tie on which the rail is mounted. Fig. 2 is a view in vertical cross section on line 2—2 of Fig. 1. Fig. 3 is a view in side 30 elevation of the rail anchor. Fig. 4 is a view in vertical section on line 4—4 of Fig. 2. Fig. 5 is a plan view similar to Fig. 1 but showing a slightly modified form of the invention. Fig. 6 is a view in transverse 35 section on line 6—6 of Fig. 5. Figs. 7 and 8 are views similar to Figs. 3 and 4 but showing the modified form of the invention illustrated on Sheet 2 of the drawings. Fig. 9 is a detail inverted plan view of the mov- 40 able jaw of the anchor.

A designates a railway rail and B denotes one of the ties on which the rail is mounted. The body C of the anchor extends beneath and bears against the bottom of the railway 45 rail and is provided at one end with a rigid jaw C' adapted to engage the base flange a of the railway rail A. The opposite end of the body member C of the anchor extends beyond the base flange a' of the rail A and 50 is provided with a projecting portion having an abutment C² adapted to bear against the side of the railway tie B. In the thickened end portion of the anchor C adjacent the abutment C² is formed a dovetail groove 55 c adapted to receive a correspondingly dove-

tailed rib d of the movable jaw D of the anchor. This movable jaw D extends over the raised portions c' and c² of the end portion of the anchor C and has an inwardly projecting part provided with an inclined face 60 d' adapted to bear against the upper surface of the base flange a' of the rail. The upper face of the raised portion c² of the anchor is formed with a series of alternating ribs and intermediate spaces c³ and c⁴ and the 65 under side of the outer portion of the movable jaw D is formed with corresponding ribs and spaces d² and d³.

In Patent No. 1,184,478, hereinbefore referred to, the movable jaw is provided with 70 serrations or teeth upon its under side adapted to engage with corresponding serrations or teeth upon the upper surface of the outer end portion of the rail anchor but it will be noted that in the present construction, the ribs and spaces c³ and c⁴ and the corresponding ribs and spaces upon the under side of the movable jaw are arranged 75 at a distance apart and are comparatively broad and shallow, the purpose of this construction being to enable the movable jaw to more readily pass over the ribs and spaces until the jaw has been forced to the position at which it will firmly engage the base 80 flange a' of the rail A.

The upper surface of the movable jaw D is formed with strengthening ribs d⁴ and between these raised ribs extends a rib d⁵, the purpose of this rib being to strengthen the 90 jaw and enable it to resist the blows of the hammer by which the jaw D is forced to firm engagement with the base flange a' of the rail.

The groove c and the tongue or rib d are inclined downwardly and inwardly toward 95 the base flange of the rail A, the purpose of this being to insure that as the movable jaw is forced to position for use, it will move downwardly and inwardly toward the base of the rail and will thus more effectively 100 grip the flange a' of the rail as the jaw D is driven to its seat.

In applying my improved rail anchor to a rail, the body portion of the anchor is passed beneath the base of the rail and the 105 fixed jaw C' is engaged with the base flange a of the rail in the usual manner, the body C of the anchor being lifted into bearing with the under side of the rail base; after which the tongue or rib d of the movable 110

2
jaw is inserted into the groove *c* and the jaw *D* is then driven toward the abutment *C*² by a hammer until the inwardly projecting portion of the jaw firmly engages 5 and grips the flange *a'* of the rail *A*. As the jaw *D* is thus forced to position to firmly engage the rail, the ribs *d*² on the under side of the jaw *D* ride over the shallow ribs *c*³ on the upper surface of the end of the 10 anchor *C* but as the jaw reaches its final position, the interlocking of the ribs *c*³ and *d*² will insure the retention of the movable jaw against danger of accidental displacement.

15 In the form of the invention illustrated in Fig. 1, the groove *c* and the tongue or rib *d* are located above the upper surface of the body portion of the rail anchor *C*, but in the form of the invention shown on 20 Sheet 2 of the drawings, the groove *c* and the tongue or rib *d* are located partially above and partially below the upper surface of the body member *C* of the anchor. So, also in the form of the invention shown 25 on Sheet 2 of the drawings, the movable jaw *D* has its outer portion formed with a depending flange *d*⁶ upon the under surface of which are formed the ribs *d*² and spaces *d*³ that interlock with the corresponding 30 ribs *c*³ and spaces *c*⁴ at the end of the rail anchor. So, also, in this form of the invention, the inner portion of the movable jaw *D* is provided with a depending flange *d*⁷ which is adapted, when the jaw is forced 35 firmly to position for use, to engage the edge of the base flange *a'* of the rail while the inner portion *d*⁷ of the jaw bears against the upper surface of the base flange *a'*. In order to permit the groove *c* to be formed 40 below the line of the upper surface of the body portion *C* of the anchor, the adjacent end portion of the anchor is formed with a downwardly extending body of metal *c*⁸, as clearly shown in Figs. 6, 7 and 8 of the 45 drawings.

By locating the groove *c* in the body member of the anchor and by forming the tongue or rib *d* upon the movable jaw, the parts can be more readily cast than where 50 the groove is formed in the movable jaw and the tongue or rib on the body member, as in the construction set forth in my hereinbefore mentioned patent.

Having thus described my invention, what 55 I claim as new and desire to secure by Letters Patent is—

1. A rail anchor comprising a body member adapted to extend beneath the rail base and having means at one end for engaging 60 one of the base flanges, and a forwardly projecting tie engaging abutment adjacent its opposite end, the said opposite end of said member being arranged to project beyond the adjacent base flange of the rail 65 and having an upwardly opening, dovetail

groove, and a wedge member having a depending, relatively narrow dovetail rib on its under side arranged to enter said groove, said rib and said groove being arranged outside the adjacent base flange of the rail 70 and being inclined relatively thereto, and said members having portions inside of said rib and groove arranged to grip the adjacent base flange of the rail between them.

2. A rail anchor comprising a body member adapted to extend beneath the rail base and having a jaw at one end for engaging one of the base flanges, the opposite end of said member being arranged to project beyond the other base flange, and having an 80 upwardly facing dovetail groove, and a wedge member having a depending dovetail rib on its under side arranged to enter said groove, said rib and groove being inclined, and said members having portions inside of 85 said rib and groove for gripping the rail flange between them, and said members also having co-operating locking surfaces outside of said rib and groove.

3. A rail anchor comprising a body member adapted to extend beneath the rail base and having means at one end for engaging one of the base flanges, the opposite end of said member being arranged to project beyond the other base flange and having a 90 dovetail groove, a wedge member above the projecting end portion of said body member and having a depending dovetail rib on its under side arranged to enter said groove, said rib and said groove being arranged outside of the adjacent base flange of the rail and being downwardly and inwardly inclined relatively thereto, and said members being arranged to grip the adjacent base 95 flange of the rail between them. 100

4. A rail anchor comprising a body member adapted to extend beneath the rail base and having a jaw at one end for engaging one of the base flanges, the opposite end of said member being arranged to project beyond the other base flange and having a thickened portion projecting upwardly above the upper face of said body member, said thickened portion being provided with an upwardly opening, dovetail groove, and a wedge member having a depending dovetail rib arranged to enter said groove, and a portion projecting inwardly therefrom arranged to overlie the adjacent base flange of the rail, said rib and groove being inclined, and the portions of said members inside of said rib and groove being arranged to grip the adjacent base flange of the rail 115 between them. 120

5. A rail anchor comprising a body member adapted to extend beneath the rail base and to engage the flanges thereof, said body member being provided at one end with a transverse groove, and a movable jaw arranged above said body member and pro- 125 130

vided upon its under side with a depending rib to engage with the groove of the body member and being provided at its outer side with a depending flange extending below the raised portion of the adjacent outer end of the body member and adapted to engage with a horizontally extending end portion of the body member.

6. A rail anchor comprising a body member adapted to extend beneath the rail base and to engage the flanges thereof, said body member being provided at one end with a transverse groove, and a transversely movable jaw arranged above said body member and provided upon its under side with a depending rib to enter the groove of the body member, said jaw having an inwardly projecting portion to engage the top of the base flange of the rail and having adjacent said inwardly projecting portion a depend-

ing flange to engage the outer edge of the base flange of the rail.

7. A rail anchor comprising a body member adapted to extend beneath the rail base and having means at one end for engaging one of the base flanges, said member having a thickened opposite end portion provided with a dovetail groove, and a wedge member having a depending dovetail rib arranged to engage said groove and a portion projecting inwardly from said rib arranged to overlie the adjacent base flange of the rail, said rib and groove being inclined and said members having portions inside of said rib and groove for gripping the adjacent base flange of the rail and said members having engaging portions outside of said rib and groove having shallow, rounded, spaced, interlocking ribs.

WILLIAM M. MITCHELL.
